(57) **CLAIM**

The ornamental design for a packaging for a single dose personal care product, as shown and described.

DESCRIPTION

FIG. 1 is a perspective view of a packaging for a single dose personal care product, showing our new design;

FIG. 2 is a second perspective view of the packaging of FIG. 1;

FIG. 3 is a front view of the packaging of FIG. 1;

FIG. 4 is a first side view of the packaging of FIG. 1;

FIG. 5 is a back view of the packaging of FIG. 1;

FIG. 6 is a second side view of the packaging of FIG. 1;

FIG. 7 is a third side view thereof of the packaging of FIG. 1; and,

FIG. 8 is a fourth side view of the packaging of FIG. 1.

The evenly spaced broken lines are shown for the purpose of illustrating parts of the article that form no part of the claim.

1 Claim, 2 Drawing Sheets
